(57) **CLAIM**

The ornamental design for a glass bead fishing tackle, as shown and described.

DESCRIPTION

FIG. 1 is a rear upper perspective view of one embodiment of a glass bead fishing tackle with a fish hook and eyes; FIG. 2 is a front upper perspective view thereof; FIG. 3 is a right side view thereof, the left side view being a mirror image of the left side; FIG. 4 is a bottom view thereof; FIG. 5 is a top view thereof; FIG. 6 is a front view thereof; FIG. 7 is a rear view thereof; FIG. 8 is a rear upper perspective view of a second embodiment of a glass bead fishing tackle with a fish hook and eyes, the other views of the second embodiment are similar to FIGS. 3-7 except that the body has a circular profile instead of an oblong profile; FIG. 9 is a front upper perspective view of the fishing tackle of FIG. 8; FIG. 10 is a front upper perspective view of a third embodiment of a glass bead fishing tackle having a through-tube; FIG. 11 is a top view of the fishing tackle of FIG. 10, the bottom view being a mirror image of the top; FIG. 12 is a right side view of the fishing tackle of FIG. 10, the left side view being a mirror image of the left side; FIG. 13 is a front view of the fishing tackle of FIG. 10, the rear view being a mirror image of the front; FIG. 14 is a front upper perspective view of the fishing tackle with a pair of eyelets; FIG. 15 is a front upper perspective view of the fishing tackle with a transverse eyelet; and, FIG. 16 is a front upper perspective view of the fishing tackle with a transverse hook and eyes. The broken lines and the diamond-shaped patterns are for illustrative purposes only and form no part of the claimed design.
